(57) **CLAIM**

The ornamental design for a tie and handkerchief retail combination, as shown and described.

DESCRIPTION

FIG. 1 is a front elevation view of a tie and handkerchief retail combination showing my new design;

FIG. 2 is a rear elevation view thereof; and,

FIG. 3 is a left side elevation view thereof.

The hanger shown in broken lines in the drawings and the interior sides of the tie and handkerchief shown in broken lines in FIG. 3 are portions of the tie and handkerchief retail combination that form no part of the claimed design.
